UNITED STATES PATENT OFFICE.

HERBERT V. LEAHY, OF LOS ANGELES, CALIFORNIA, ASSIGNEE, BY MESNE ASSIGNMENTS, TO FRED BROWN AND HERBERT V. LEAHY.

CARBURETOR.

Application filed January 9, 1920. Serial No. 350,278.

To all whom it may concern:

Be it known that I, HERBERT V. LEAHY, a citizen of the United States, residing at Los Angeles, in the county of Los Angeles and State of California, have invented a new and useful Carburetor, of which the following is a specification.

The object of this invention is to provide a construction in which a primary annular air current of constant volume is directed 10 transversely across an annular fuel discharge throat of a fuel feed device, for lower engine speeds or power, and combining therewith, beyond the fuel discharge throat, 15 a variable main air current for higher engine speeds or power.

Another object is to direct said currents against a spreader head and to provide an 20 automatic control valve co-operating with said head and operable by the suction of the engine.

Various other objects relate to the provision of means for breaking up the fuel into 25 a maximum number of minute particles to produce an intimate mixture of fuel and air, and to various features of adjustment and regulation contributing to the production of a carburetor of simple construction and of great flexibility of control.

30 Numerous other advantages will be more fully apparent from the following detailed description of the accompanying drawings which form a part of this disclosure and which illustrate a preferred form of embodiment of the invention.

Of the drawings:

Fig. 1 is a side elevation of my improved carburetor.

Fig. 2 is a top plan view.

40 Fig. 3 is an end elevation.

Fig. 4 is a central longitudinal section.

Fig. 5 is a section on line x^5-x^5 of Fig. 4.

Fig. 6 is a detailed elevation of the fuel feed device.

45 Fig. 7 is a section on line x^7-x^7 of Fig. 6.

Fig. 8 is a section on line x^8-x^8 of Fig. 4.

Fig. 9 is a detailed elevation of the flanged thimble of the fuel feed device.

Fig. 10 is a detailed elevation of the mixing tube.

Fig. 11 is a detailed elevation of the "high speed" valve.

Fig. 12 is a detailed perspective view of the adjustable fuel spraying sleeve.

Fig. 13 is a detailed perspective view of the lock sleeve.

Fig. 14 is a transverse section on line $x^{14}-x^{14}$ of Fig. 1.

The carburetor casing 1, provides a float chamber 2 and a mixing chamber 3 having 60 an air inlet port 4 and a mixture outlet port 5 for communication with the intake manifold of an engine. The float chamber 2 contains a valve controlling float 6 functioning to maintain a constant liquid level 65 therein.

No further detailed description of the float mechanism will be herein given as the specific details of such mechanism will form the subject matter of a separate application and for the reason that any well known float mechanism may be utilized in connection with the present invention.

The float chamber connects by a pipe line 7, with a fuel supply nozzle tube 8 having 75 a port 9 controlled by a needle valve 10. Said needle valve has a screw-thread engagement with the base of the nozzle tube to provide for a longitudinal adjustment of the valve for control of the port 9. A bushing 11, forming the bottom wall of the mixing chamber, has a screw-thread engagement with the casing and the nozzle tube 8 is screw-threaded into a central base in said bushing and retained in position by a lock 80 nut 12.

The upper end of the nozzle tube 8, beyond the port 9, forms a secondary fuel passage 13 and the walls of said passage are provided with a plurality of radial fuel orifices 14. This construction provides a fuel supply nozzle tube communicating with the float chamber and having a secondary fuel passage controlled by a needle valve, the secondary fuel passage discharging the fuel 95 through the radial fuel orifices.

Mounted upon and surrounding the nozzle tube 8 there is provided a tubular spraying device comprising a sleeve 15 (see Fig. 12) screw-threaded and adjustable on the 5 nozzle tube, and a spreader head 17 screw-threaded upon the upper end of the nozzle tube. The opposed edges of the sleeve 15 and the head 17 provide an annular discharge throat 18 and are oppositely beveled 10 inwardly to form an intermediate annular fuel chamber 19 communicating with the radial fuel orifices 14 of the nozzle tube 8. By axially adjusting the sleeve 15, the area of the discharge throat 18 can be varied as 15 desired and after such adjustment has been made the sleeve is retained in its adjusted position by a lock sleeve 20 (see Fig. 13) which has a screw-thread engagement with the tube 8 immediately below the sleeve 15. 20 The fuel is drawn from the discharge throat 18 by a primary air current entrained across said throat, as will next be explained, said air current spraying the fuel into the mixing tube where it is combined with the 25 main air supply.

As will be seen by reference to Figs. 4, 12, 13, the sleeves 15 and 20 are of equal diameter, their peripheries presenting a smooth unbroken surface. Slidable on said 30 sleeves is a flanged thimble 21 having an upper beveled surface 22 and a screw-threaded flange 23 having a plurality of vertical air passages 24 and an extended rim 25. Said thimble is clamped to the sleeve 20 in 35 adjusted position by a set screw 26.

A cone-sleeve 27 has a screw-thread engagement with the screw-threaded flange 23 of the thimble 21 and forms the outer wall of a primary annular air passage 28. The 40 cone sleeve has a beveled wall portion 29 co-operating with the beveled surface 22 of the thimble 21, as a valve, to control the volume of the primary air current passing through the air passage 28.

45 The sleeve 27 is provided with recesses 30 to accommodate any suitable wrench or tool for turning said sleeve and by such turning the sleeve will be longitudinally adjusted on the thimble. The extended rim 50 25 of the thimble 21 has a notched outer periphery and secured to the lower portion of the cone sleeve 27 is a spring detent 31 adapted to engage said notches to maintain the cone sleeve in adjusted position. (See 55 Figs. 6-8.)

With reference to Fig. 4, it will be seen that the thimble 21 is spaced from the bushing 11 providing an air passage 32 communicating with the main air supply portion of the mixing chamber.

60 The primary air current is drawn upwardly through the vertical air passages 24 in the thimble 21 and the primary air passage 28, and past the annular discharge throat 18 of the fuel nozzle. This action

draws the fuel from the discharge throat and directs the mixture upwardly against the surface of the spreader head 17 where it will be combined with the main air supply current from the air port 4.

70 The control of the volume of the main air supply current will now be explained. A mixing tube 35 has a flanged upper end by which it is secured in position by screws 36 extending through elongated slots 37 in the main casing and screw-threaded into the flange. This connection provides for a longitudinal adjustment of the tube. The lower edge of said tube is notched to provide depending legs 38 and intermediate air 75 ports 39. The legs 38 extend downwardly approximately to a position of contact with the surface of the cone sleeve 27, the combined area of the several air ports 39 providing a maximum main air supply. A vertically movable valve sleeve 40 surrounds the tube 35 and is movable downwardly to 80 reduce the area of the ports 39, said ports being entirely closed when the sleeve is in extreme lower position.

85 The means for operating the valve sleeve 40 comprises a lever 41 having a forked inner end which is pivotally connected to opposite sides of the valve sleeve by pivot screws 42. (See Fig. 5). The outer end of 90 said lever is pivoted to a stationary bracket 43 and at an intermediate point is pivotally connected to a vertically movable push rod 44. The rod 44 extends upwardly through the casing and is connected with an eccentric 100 strap 45 surrounding and operated by an eccentric cam 46 fixed to a throttle valve shaft 47. The rod 47 is journaled in the casing and has secured thereto the usual throttle valve 48 positioned in the mixture 105 outlet port 5. A spring 49 interposed between the casing and a collar 50 on the rod 44, assists in returning to upper position and the throttle valve rod 47 has secured thereto a lever 51 which is connected to any suitable operating means, such as the throttle lever of an automobile. This mechanism provides for a regulation of the volume of the main air supply commensurate to regulation 110 of the throttle valve.

115 To control the volume of mixture drawn from the carburetor there is provided an automatic suction-operated control valve 55, as a so-called "high-speed" valve, operating in varying degrees coincident to the suction 120 created by the engine. The valve 55 which is of sleeve formation, is slidably positioned in the upper portion of the mixing tube 35 between the throttle valve and the spreader head and is yieldingly maintained in downward position, contacting with the mixing tube 35, as shown in dotted lines in Figure 4, by a spring 56. The spring engages the lower flanged portion of the valve and also engages a collar 59 which forms a guide for 125 130

the upper portion of the valve. The collar 59 is attached to the casing by screws 60 which extend through elongated slots 61 providing for a longitudinal adjustment of the collar to regulate the tension of the 5 spring. The lower portion of the valve 55 is turned inwardly to provide a restricted throat and beveled surfaces 58 which cooperate, as a valve, with the beveled surface 10 57 of the spreader head.

Having described in detail the mechanism as illustrated, an explanation of the general operation of the device will now be set forth.

Assuming that the carburetor is connected 15 to the intake manifold of an internal combustion engine and that the throttle valve 48 and main air control valve 40 are closed, (the closed position of the throttle valve not entirely closing the outlet port 5) the operation 20 is as follows: The engine is cranked in the usual manner and the comparatively slight suction produced in the mixing chamber will draw the primary air current from the passage 32, upwardly through the vertical air passages 24, annular air passage 28, the exit of which is regulated by the valve 25 formed by the cooperating beveled wall surfaces 22 and 29, and past the fuel discharge throat 18. This primary air current draws the fuel from the throat 18 and directs the 30 mixture upwardly against the peripheral surface of the spreader head 17. The fuel from the float chamber flows upwardly in the nozzle tube 10, through the valve controlled 35 port 9 to the secondary fuel passage, and outwardly through the radial fuel orifices 14 to the annular fuel chamber 19.

To increase the speed of the engine, the 40 throttle valve 48 and main air supply valve 40 are simultaneously opened. The opening of the throttle valve serves to increase the degree of vacuum in the mixing chamber with the result that the automatic "high-speed" valve 55 will be raised to a corresponding 45 degree to permit a greater volume of mixture being drawn through the mixing chamber and the opening of the air valve 40 provides for the admission of additional air to the mixing tube. It will be clear that the 50 main air current from the air port 4, in passing through the several air ports 39, will be deflected upwardly by the cone-sleeve 27 and directed against the surface of the spreader-head 17 when it combines with the

mixture from the primary air passage 28, the 55 combined mixtures being broken up into exceedingly small particles by contact with the spreader-head and again by direct impact against the valve 55.

The adjustment of the spring 56 of the 60 "high-speed" valve 55 is such that the valve will readily accommodate itself to the varying degree of vacuum in the mixing chamber and is also such that in case the throttle valve is very suddenly closed the valve 55 65 will function quickly to closed position and reversely, if the throttle valve is very suddenly fully opened the action of the valve 55 will be relatively sluggish so that the engine will not be suddenly flooded with a full supply of fuel but will be supplied with a more 70 gradually increasing supply of fuel as the speed of the engine increases.

Having described my invention, I claim:

A carburetor combining a casing providing a mixing chamber having an air inlet port and an outlet port, a nozzle tube forming a main fuel passage and a secondary fuel passage, a valve controlling communication between said passages, a sleeve adjustable on the tube, a spreader-head carried by the tube, the adjacent edges of said sleeve and head forming an annular fuel discharge throat and beveled inwardly to provide an intermediate annular fuel chamber, the nozzle 75 having radial fuel orifices establishing communication between the secondary fuel passage and the intermediate annular fuel chamber, a thimble surrounding and longitudinally adjustable relative to the sleeve 80 and having a beveled annular surface, a cone-sleeve surrounding and longitudinally adjustable on the thimble, said cone-sleeve defining an annular primary air passage 85 and having a beveled surface cooperating with the beveled surface of the thimble as a valve to control the primary air passage, a mixing tube defining an annular main air passage surrounding the cone-sleeve and having air supply ports, and a tubular valve 90 operative to control the area of the air supply ports.

Signed at Los Angeles, California, this 28th day of November, 1919.

HERBERT V. LEAHY.
